UNITED STATES PATENT OFFICE.

ARTHUR LEE COLLINS, OF SAN FRANCISCO, CALIFORNIA.

WELL.

1,094,532.

Specification of Letters Patent. Patented Apr. 28, 1914.

Application filed January 21, 1913. Serial No. 743,309.

To all whom it may concern:

Be it known that I, ARTHUR LEE COLLINS, a citizen of the United States, residing at San Francisco, county of San Francisco, 5 State of California, have invented new and useful Improvements in Wells, of which the following is a specification.

This invention relates more particularly to the installation of wells for use in pumping ground water for irrigation and domestic uses; but each of the improvements composing the invention, is intended to be secured for all the uses to which it can be applied with or without modification, and 15 will apply particularly to water wells and oil wells.

The drawing represents a well and well casing in vertical section.

In making a well for the purpose of taking 20 water from porous, materials for which bored wells for the most part at least have been employed, it has been customary to bore through the alternate clay, gravel and rock beds and case the well with a metal or 25 manufactured cylindrical casing to a suitable depth. The well hole may be cased in part or as a whole.

Water flowing through gravel and sand or 30 porous materials, is retarded by the friction or so-called resistance that the surface of the integrate particles of sand and gravel offers to the flow of the water. The amount of water that will flow through a given area of sand or gravel, will depend essentially upon 35 the pressure head of the water, the area of air space and the relation of this air space to the surface area of the integrate particles. Solid particles submerged in water, although heavier than water, may be set in 40 motion by the moving water, due to this force that is offered by the surface of the particles. Holes or perforations when placed below or on the same level in the casing with the porous or loose strata permit 45 sand or other materials to slide into the well with the water and fill up the well hole. The number of particles entering the casing will depend in a measure upon the velocity of the water.

50 In boring a well, one or more porous strata may be encountered, which strata for example will be from one to fifty feet or more in depth. In order to draw the largest amount of water from a well, each stratum should be developed by taking out the finer particles and decreasing the resistance

to the water. However, the continual pumping of sand will subject the roof above the sand or gravel strata to caving. There may also be provided a means for agitating 60 the finer particles composing the porous strata with a water, steam or air jet, or by a mechanical means and the substitution, although not necessary in each case, of coarse gravel, charcoal or suitable materials 65 in the place of finer particles, either as a means to increase the resistance of the fine particles as they pass over the larger ones, or the regulation of the amount of the water. 70

The collars and casings as shown, will separate the different sand strata. Also by making use of the apparatus as described and causing the particles of sand to move in a vertical direction before entering the 75 well hole, the particles will not be sluiced directly into the well hole. The added resistance due to gravity force, will counteract in a measure, the force of the water. A means is provided for the cutting off of the 80 lower casing as shown, so that the water will be drawn from the upper strata.

The construction and operation of the well is as now described, but it will be understood that additions, omissions and modifications may be made indefinitely within the limits of the invention so long as the substance of any one or more of the hereinafter written claims is taken. 85

P¹, P², P³, P⁴, P⁵, P⁶, P⁷ are porous water 90 bearing strata. Casing A may have been lowered to stratum P⁵ or any other stratum and later, after substituting casings B and I, withdrawn to stratum P¹ as shown. Casings B, etc., may be placed without the aid 95 of outer casings. Casings such as J and K may also be placed without the aid of outer casing. As an example, casing K can be made up of a length which will reach from top of well and after being seated, as shown, 100 can be cut off or separated by means of a suitable tool. The attached collars C, E, and G, are for the purpose of sealing off the adjacent strata.

To aid the collar in sealing off the different 105 strata, gravel or suitable materials can be lowered inside of casing A, and outside of casing B. To permit of a series of ring seals, the upper ring may be perforated to act as a screen and to allow the graded particles, for example, to pass through collar C and collar E and be retained at collar G. 110

By using large perforations in collar C and smaller ones in collar E, the collar C will retain large particles, while collar E will retain a smaller size and collar G the remainder, thus aiding to seal off the different strata.

D and F are perforations for permitting water to enter casing. They may be of such size as will permit the entrance of suitable materials from inside of well casing to outer water pocket.

Collar H, is a safety collar to prevent the well surface about the strata from caving in and filling up the lower strata.

15 I, is an expanded casing which acts as a collar and also as a means of providing for an inner casing called J.

Casings J and K, are a series of inner casings, each stratum having its outlet as 20 shown at P⁶ and P⁷.

In regulating the flow of water and sand in porous strata, suitable materials can be placed between inner and outer casing.

L, is a cap or plug and may be the form of 25 a cylinder or suitable form just filling casing K and suspended from above and used as a seal to cause more or less water to be pumped from stratum P⁶ and upper strata, and in addition, made in such form as to 30 act as a receptacle to collect the sand or fine materials entering well casing above. The number of strata that can be developed in this manner is unlimited.

I claim as my invention and discovery:

35 1. In a well having successive water strata, a well casing comprising a vertical series of separate cylindrical casing sections concentrically arranged and successively of larger diameter from the lowermost upward, each section extending up within and spaced from the section above it forming an entrance opening, and the lower end of each section terminating substantially at the upper limit of a stratum.

40 2. In a well having successive water strata, a well casing comprising a vertical series of separate cylindrical casing sections

concentrically arranged and successively of larger diameter from the lowermost upward, each section extending up within and spaced from the section above it forming an entrance opening, the lower end of each section terminating substantially at the upper limit of a stratum, the uppermost section being annularly reduced at its top portion, 50 and a cylindrical casing section larger in diameter than said reduced portion extending down over the top thereof and spaced therefrom and from the sides of the well and extending upwardly toward the top of 55 the well, said latter casing section being circumferentially perforated at intervals between successive water strata and having collars attached thereto for packing off each stratum from discharging fluid downwardly.

3. In a well having successive water strata, a well casing comprising a vertical series of separate cylindrical casing sections concentrically arranged and successively of 60 larger diameter from the lowermost upward, each section extending up within and spaced from the section above it forming an entrance opening, the lower end of each section terminating substantially at the upper limit of a stratum, and a cap for closing the top of any desired section whereby water from lower strata and casing sections may be cut off.

4. A well casing comprising a cylindrical 70 section adapted to be spaced from the sides of a well and circumferentially perforated at predetermined intervals whereby said perforated portions will be located between successive water strata, and annular collars 75 on said casing between said perforated portions whereby water strata may be packed off from discharging downwardly.

ARTHUR LEE COLLINS.
